UNITED STATES PATENT OFFICE.

ARCHIA L. ROSS, OF NEW YORK, N. Y.

DESIGN FOR A TROUSERS-HANGER.

SPECIFICATION forming part of Design No. 32,533, dated April 17, 1900.

Application filed February 26, 1900. Serial No. 6,647. Term of patent 14 years.

To all whom it may concern:

Be it known that I, ARCHIA L. ROSS, a citizen of the United States, and a resident of the city of New York, borough of Manhattan, in 5 the county and State of New York, have invented and produced a new and original Design for a Trousers-Hanger, of which the following is a full, clear, and exact description.

Reference is to be had to the accompanying 10 drawing, forming a part of this specification, in which the figure is a perspective view of the design.

The design in its entirety consists of the inverted-U-shaped end bars A and B, having 15 eyes A' and B', respectively, and the corrugated spaced side bars C and D, arranged parallel one to the other, the side bar C being on a somewhat-higher plane than the side bar D, and the said bars are formed with pairs of 20 downwardly-extending loops E E', an upwardly-rising loop E² being between the loops

E E' of each pair, and a separating-bar E³, extending between the pairs of loops, the pairs of loops of the two side bars C and D being located opposite each other. 25

The leading feature of the design consists of the spaced side bars having pairs of downwardly-extending loops and a separating-bar between adjacent pairs of loops.

Having thus fully described my invention, 30 I claim as new and desire to secure by Letters Patent—

The design for a trousers-hanger, as herein shown and described.

In testimony whereof I have signed my 35 name to this specification in the presence of two subscribing witnesses.

ARCHIA L. ROSS.
